IMPLEMENT SUPPORTING FRAME FOR TRACTORS

George W. Mork, South Milwaukee, Wis., assignor
to Bucyrus-Erie Company, South Milwaukee,
Wis., a corporation of Delaware

Application June 10, 1948, Serial No. 146,893

Term of patent 14 years

(Cl. D14—3)

To all whom it may concern:

Be it known that I, George W. Mork, a citizen of the United States, residing at South Milwaukee, county of Milwaukee, State of Wisconsin, have invented a new, original, and ornamental Design for an Implement Supporting Frame for Tractors, of which the following is a specification, reference being had to the accompanying drawing, forming part thereof.

In the drawing:

Figure 1 is a side elevational view of an implement supporting frame for tractors, showing my new design.

Figure 2 is a top plan view of the same.

Figure 3 is a rear elevational view of the same.

Figure 4 is a front elevational view of the same.

The side of the implement supporting frame opposite that shown in Figure 1 presents substantially the same appearance as that depicted:

I claim:

The ornamental design for an implement supporting frame for tractors, as shown and described.

GEORGE W. MORK.
